(57) **CLAIM**

The ornamental design for a wireless charger, as shown and described.

DESCRIPTION

FIG. 1 is a front, top perspective view of a wireless charger, showing my new design;

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is an enlarged view of the area labeled **9** in FIG. 1; and,

FIG. 10 is an enlarged view of the area labeled **10** in FIG. 1.

The dashed lines in the figures illustrate portions of the wireless charger that form no part of the claimed design. The dot-dash broken lines of the wireless charger in FIG. 1 illustrate a boundary and cut line of the enlarged detail view in FIG. 9 and FIG. 10 and form no part of the claimed design.
